LIQUEFIED GAS DISPENSING SYSTEM

James C. Fleming, Lubbock, Tex., assignor of one-half to Robin Baker, Plainview, Tex.

Application May 22, 1944, Serial No. 536,760

7 Claims. (Cl. 62—1)

1

This invention relates to an improvement in liquefied gas dispensing systems, such as may be used for vaporizing and dispensing liquefied gases of the type of butane or butane mixtures.

Such liquefied gases are ordinarily held in liquid form within a tank, frequently buried underground, under sufficient pressure to maintain the gas in liquid phase. Then when the gas is withdrawn from the tank and its pressure reduced, it flashes into vapor which may be conveyed to the burner or point of use. These systems have usually required some form of vaporizer to aid in vaporizing the liquid withdrawn from the tank, and/or after its pressure is reduced. Where this vaporizer is mounted in the tank or attached thereto, the construction is expensive and has other objectionable characteristics.

An object of this invention is to simplify and improve the construction of the liquefied gas system to enable the equipment to be manufactured inexpensively, to be assembled without difficulty and be repaired when desired without disturbing the installation of the storage container.

A further object of the invention is to provide a thermo-syphonic circulating system for utilizing the liquid in the tank in aiding the vaporization of the withdrawn liquefied gas, but in a manner which will nevertheless maintain a circulation of warm liquid from within the tank in heat exchange relation with the vaporized gas. This is accomplished by positioning the vaporizer in an upright position over the tank and circulating the vaporized fuel downwardly therethrough in heat exchange relation with the liquid in the vaporizer so as to facilitate the thermo-syphonic circulation therethrough of the liquid in the tank.

The vaporizer is also mounted detachably relative to the tank so that it may be disconnected therefrom for repair, and the first-stage pressure reducing regulator is so arranged with respect to the vaporizer that it will facilitate the thermo-syphonic circulation, but it will also utilize the warming effect of the liquefied gas withdrawn from the tank in thermo-syphonic circulation to warm the port of the first-stage regulator and tend to prevent freezing thereof.

An embodiment of the invention is illustrated in the accompanying drawing which represents a partial vertical section through a liquefied gas tank showing the invention applied thereto, with parts in elevation.

The pressure storage tank is designated generally by the numeral 1 and is of the character ordinarily used for storing highly volatile liquefied petroleum gas, such as butane or a mixture con-

taining butane. The tank 1 may be buried underground as usual, if desired, which is often required to maintain practical operation continuously, particularly in cold climates. The tank 1 is adapted to be filled and gauged in the usual way, as by the stand-pipe 2, having a head 3 thereon provided with the usual fittings for filling, gauging the pressure, etc. Where the tank is buried underground, these parts are usually enclosed within a surrounding casing provided with a removable cover for access thereto.

In the example shown, the tank 1 is provided with a heat exchanger, designated generally at 4, which is constructed as an enclosed casing or container surmounted on the tank, detachable therefrom, by means of a coupling or union 5. The heat exchanger 4 is elongated vertically in upstanding relation from the top of the tank. The lower end of the heat exchanger 4 is detachably connected by the union 5 with the upper end of a return pipe 6 extending upwardly through the top of the tank and preferably welded thereto. The return pipe 6 has a cut-off valve 7 therein. The return pipe 6 extends downwardly in the tank 1 to a point near the bottom thereof.

Mounted upon the upper end of the heat exchanger 4 is a chamber 8, detachably connected with the heat exchanger 4, as by a union 9. These parts 4, 6 and 8 are thus detachable from each other, capable of being separated for detachment of the chamber 8, as well as the heat exchanger, from the other parts of the system, particularly when repair may be necessary or desirable, without disturbing the storage tank 1. The separate construction and detachable connection of the top chamber 8 and heat exchanger 4 facilitates the construction of the system in an economical manner, as well as repair of any of these parts readily.

40 The chamber 8 has a withdrawal pipe 10 connected with a side thereof and extending downwardly therefrom beside the heat exchanger 4 through the top of the tank 1 to which it may be welded, if desired, and to a point adjacent the bottom of the tank, as indicated in the drawing. This pipe 10 will supply liquefied gas from within the tank to the chamber 8, as hereinafter described.

45 The withdrawal pipe 10 has a cut-off valve 11 therein preferably located adjacent the top of the tank to provide a detachable connection of the super-structure therewith, as well as to control or discontinue the flow. The pipe 10 is detachably connected with the chamber 8 by means

of a union 12 to permit the chamber to be disconnected therefrom.

The pipe 10 also is provided with a T 13 therein connected by a return tube 14 extending therefrom to the head 3 for communication to the stand-pipe 2, with the connection from said return tube 14 to the stand-pipe 2 controlled by a valve 15 in the head.

Also mounted within or at one side of the chamber 8 is a pressure reducing regulator, designated generally at 16, which is shown as of the usual form of diaphragm-operated valve having adjusting springs acting thereon, so as to control the passage of fuel therethrough. The regulator 16 has an inlet at 17 to one side of the valve thereof, and an outlet at 18 from the opposite side of the valve thereof. The inlet 17 is located at or substantially above the highest point of the withdrawal pipe 10 and the point of connection thereof with the chamber 8.

Extending from the outlet 18 and connected therewith, is a tube 19 that extends downwardly through the vaporizer 4 substantially throughout the length thereof and is turned back and outwardly therefrom at the top thereof. The tube 19 preferably has an extended length within the vaporizer container 4, such as will be provided by a coil 20, to aid in the transfer of heat from the liquid within the vaporizer container to the gas or liquid within the coil. The tube 19 extends from the vaporizer 4 to a second-stage pressure regulator 21, which may be of the usual character employed in liquefied gas dispensing systems, shown as mounted on the stand-pipe 2. From said regulator 21 a service pipe 22 extends to the gas burner or other point of use.

The chamber 8 is in open communication with the chamber in the vaporizer 4, through nipples connected together by the union 9.

The liquefied gas is confined in the tank 1 under a pressure of approximately forty pounds per square inch. The first-stage pressure reducing regulator 16 is set ordinarily to operate at approximately five pounds per square inch. The second-stage pressure reducing regulator 21 is set to operate ordinarily at approximately six ounces.

When no gas is being consumed at the burner or drawn off from the service pipe 22 and the system is dormant, the liquid will stand at approximately the same height in the pipes 6 and 10. However, when gas is being consumed, this will reduce the pressure in the pipe 19-22 which will then operate to open the valve in the regulator 16, and this in turn will decrease the pressure in the chamber 8 and vaporizer 4, as well as in the pipes 6 and 10. This reduction in pressure will cause the liquid to rise in the pipes 6 and 10 due to the suction thus caused therein until the liquid from the tank 1 fills these pipes and also the vaporizer 4 and chamber 8, passing into the inlet 17 of the regulator 16.

As the liquefied gas passes through the regulator 16, the reduction in pressure on the outlet side thereof is sufficient to cause an expansion of the gases to vaporization thereof, and the vaporized gases then pass off through the tube 19 to the point of use. Refrigeration takes place in the chamber 8, because of the expansion of the gases at the regulator, and the expanded gases passing through the coil 20 often have a temperature below freezing, and sometimes are accompanied by some liquid which fails to vaporize or which may become liquid again after leaving the regulator. The lower temperature

thus present in the coil 20 than is present in the liquid in the vaporizer 4, causes some of the heat from the liquid in the vaporizer to be given up to the gas in the coil, thus aiding in vaporizing or maintaining the vaporizing of the gas therein.

As the heat from the liquid in the vaporizer 4 is thus given up to the coil 20, the liquid in the vaporizer will be cooled at its lower portion with respect to the liquid that enters the upper part of the structure 4, 8, so that the cooler liquid will have a tendency to move downward through the pipe 6 into the tank. This in turn will allow a circulation of warm liquid from within the tank upward through the withdrawal pipe 10 into the chamber 8.

After the system is in operation, this thermosyphonic circulation will continue to be maintained, thereby circulating warmed liquid from within the tank into the vaporizer 4 in heat exchange relation with the tube 19 and coil 20, to vaporize the gas passing therethrough or any part of said gas that may require vaporization.

This system will also cause circulation of warmed liquefied gas around the outside of the regulator 16, the portion thereof contained within the chamber 8. This circulation will be sufficient to warm the regulator at the point where refrigeration normally takes place, and thus tends to prevent the freezing of the valve of the regulator, which would otherwise impair the efficiency of the system. Moreover, it will be noted that the inlet 17 of the regulator 16 is located directly at the top of the chamber 8, so that it receives therein the warmed liquid directly from the withdrawal pipe 10. This facilitates vaporization because the warm liquefied gas vaporizes much more readily than after it has been cooled appreciably.

During the normal operation of the system on liquid withdrawal, the valve 15 will remain closed. However, the valve 15 may be opened to allow the tank pressure of vaporized gas above the liquid in the tank 1 to be turned into the thermo-circulating system, thereby forcing all liquid from within the pipes 6 and 10, the vaporizer 4 and the chamber 8, back into the tank 1. Then upon closing of the valves 7 and 11, there will be only vaporized gas in the superstructure. This will prevent the loss of any liquid when the parts are disassembled. It is also possible with this structure to disconnect the tube 14 from the T 13 and extend it from the head 3 directly to the regulator 21, when the system may be operated on batch vaporization. The vaporized fuel in the top of the tank 1 will then pass off through the stand-pipe 2 and out of the head 3, through the tube 14 directly to the regulator 21, thence to the service pipe 22. Such direct operation or batch vaporization may be desirable, for instance, when the vaporizer 4 or the chamber 8 may require disconnection for repair.

The system thus provides for more efficient vaporization of the liquefied gas, with improved operation, and yet is simple and inexpensive to construct. Moreover, the parts are detachably connected together so that they may be separated for repair without disturbing the installation of the storage tank in the ground.

I claim:

1. In a liquefied gas dispensing system, a vaporizer comprising an upright chamber adapted to contain a heat exchange medium therein, a tube extending through said chamber for circu-

lating vaporized fuel therethrough without mixture with the liquid in the vaporizer, a pressure reducing regulator mounted at the upper end of said vaporizer and having a discharge side connected with said tube and an inlet adapted to receive liquefied fuel therein, and a chamber mounted on the vaporizer and at least partially enclosing the regulator in open communication with the inlet thereof.

2. In a liquefied gas dispensing system, a vaporizer comprising an upright chamber adapted to contain a heat exchange medium therein, a tube extending through said chamber for circulating vaporized fuel therethrough without mixture with the liquid in the vaporizer, a pressure reducing regulator mounted at the upper end of said vaporizer and having a discharge side connected with said tube and an inlet adapted to receive liquefied fuel therein, a chamber mounted on the vaporizer and at least partially enclosing the regulator in open communication with the inlet thereof, said last-mentioned chamber being in open communication with the vaporizer chamber, and means for circulating liquid into the second-mentioned chamber in heat exchange relation with the regulator and downwardly through the vaporizer in heat exchange relation with the tube therein.

3. In a liquefied gas dispensing system, the combination of a tank adapted to contain liquefied gas under pressure, a substantially inverted U-shaped conduit structure having the side arms thereof extending downwardly into the tank through the top thereof to a point adjacent the bottom of the tank and open therein for thermosyphonic circulation of liquefied gas from within the tank through said conduit structure, means connected with said conduit structure for reducing the pressure of a portion of the liquefied gas circulating therethrough and vaporizing said gas for directing said vaporized gas to a point of consumption, valve means connected in the opposite sides of the inverted U-shaped conduit structure adjacent the top of the tank for closing said conduit structure against upward flow of gas therethrough from the tank, and means for detachably mounting the pressure reducing and vaporizing means and the upper portion of the conduit structure on the tank for detachment thereof from the tank upon closing of said valve means.

4. In a liquefied gas dispensing system, the combination of a tank adapted to contain liquefied gas under pressure, a substantially inverted U-shaped conduit structure having the side arms thereof extending downwardly into the tank through the top thereof to a point adjacent the bottom of the tank and open therein for thermosyphonic circulation of liquefied gas from within the tank through said conduit structure, means connected within said conduit structure for reducing the pressure of a portion of the liquefied gas circulating therethrough and vaporizing said gas and for directing said vaporized gas to a point of consumption, valves connected in the side arms of the conduit structure for closing the conduit structure against the upward flow of gas therethrough from within the tank, and means detachably mounting the pressure reducing and vaporizing means and the upper portion of the conduit structure on the tank in the conduit structure for detachment thereof from the tank.

5. In a liquefied gas dispensing system, the combination of a tank adapted to contain liquefied gas under pressure, a substantially inverted

U-shaped conduit structure having the side arms thereof extending downwardly into the tank through the top thereof to a point adjacent the bottom of the tank and open therein for thermosyphonic circulation of liquefied gas from within the tank through said conduit structure, means connected with said conduit structure for reducing the pressure of a portion of the liquefied gas circulating therethrough and vaporizing said gas for directing said vaporized gas to a point of consumption, valve means connected in the opposite sides of the inverted U-shaped conduit structure adjacent the top of the tank for closing said conduit structure against upward flow of gas therethrough from the tank, means for detachably mounting the pressure reducing and vaporizing means and the upper portion of the conduit structure on the tank for detachment thereof from the tank upon closing of said valve means, and means for directing gas pressure from the top of the tank to the top portion of the conduit structure for forcing the liquefied gas therefrom back into the tank.

6. In a liquefied gas dispensing system, the combination of a tank adapted to contain liquefied gas under pressure, a substantially inverted U-shaped conduit structure having the side arms thereof extending downwardly into the tank through the top thereof to a point adjacent the bottom of the tank and open therein for thermosyphonic circulation of liquefied gas from within the tank through said conduit structure, means connected with said conduit structure for reducing the pressure of a portion of the liquefied gas circulating therethrough and vaporizing said gas and for directing said vaporized gas to a point of consumption, pressure reducing means connected with the conduit structure for reducing the pressure of the gas and vaporizing said gas for supply to a point of consumption, a stand-pipe connected with the top of the tank and extending upwardly therefrom, a head mounted on the stand-pipe and having a control valve therein, and a tube connected with said valve and with the upper portion of the conduit structure for communication through said head from the stand-pipe to the top portion of the conduit structure.

7. In a liquefied gas dispensing system, a vaporizer comprising an elongated chamber adapted to contain a heat exchange medium therein, a tube extending through said chamber for circulating vaporized fuel therethrough without mixture with the liquid in the vaporizer, a pressure reducing regulator mounted at one end of said vaporizer and having a discharge side connected with said tube and an inlet adapted to receive liquefied fuel therein, and a chamber mounted on the vaporizer and at least partially enclosing the regulator in open communication with the inlet thereof.
